UNITED STATES PATENT OFFICE.

CHARLES HAMMER, OF HOLLIS COURT BOULEVARD, NEW YORK.

ANGULAR SIDE OR DECAGON CAP.

Application filed July 7, 1923. Serial No. 650,113.

To all whom it may concern:

Be it known that I, CHARLES HAMMER, a citizen of the United States, residing at Hollis Court Boulevard, in the county of Queens and State of New York, have invented certain new and useful Improvements in Angular Side or Decagon Caps, of which the following is a specification.

This invention relates to metal caps or closures for use with glass containers, the object of the invention being to provide a cap having a depending flange or skirt of improved polygonal form.

A further object of the invention is the provision of an improved shallow flanged cap, the flange or skirt of which is provided at its lower edge with a strengthened portion preferably in the form of a curl, roll or bead and which flange is made up of a series of connected substantially flat sides extending practically from the top of the skirt to the strengthened lower edge, and which strengthened lower edge in the form shown is provided with inwardly extending locking projections or lugs whereby the polygonal form of the cap together with the rolled or curled lower edge will very materially strengthen the cap, its flange and projections so that the cap can be made of relatively thin metal and resist distortion in the application of the cap to the container while at the same time the form of the flange will facilitate the handling of the cap and also to a material extent resist the premature turning off of the cap when turned on to a container having cooperating lugs or projections.

In the drawings accompanying and forming a part of this specification, Fig. 1 is a perspective view of this improved cap; Fig. 2 is a horizontal cross section thereof; Fig. 3 is a cross sectional view taken on line 3—3 Fig. 2; and Fig. 4 is a detail cross sectional view taken on line 4—4 Fig. 2.

Similar characters of reference indicate corresponding parts in the several views.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

This improved cap comprises a top 2 having a depending flange or skirt 3, which in the form shown is of shallow formation, and this skirt is of polygonal form, the 60 number of polygons varying with the diameter of the cap, but in one form thereof shown the skirt has preferably ten relatively substantially flat sides, and is therefore of decagonal form. The lower edge 5 of this 65 skirt is strengthened or reinforced by rolling, curling or beading it, as by bending the metal of the flange outwardly upon itself, and from this strengthened portion is formed a plurality of inwardly extending 70 locking projections or lugs 6, two thereof being shown in the present instance, and these projections are formed by suitable manipulation of the curled edge, as by forcing the metal and curled edge inwardly under suitable pressure. This pressure may be exerted either radially or transversely 75 of the cap or both, as circumstances require, whereby the rolled edge is somewhat compressed to form relatively flat faced inwardly extending projections adapted to engage 80 projections or threads of a glass container, and thus permit the cap to be turned and locked on to the container.

By the provision of the relatively flat or angularly formed portions 4 in the flange, the flange and the cap are materially strengthened as well as providing a gripping surface for the handling of the cap, and the rolled edge adjacent to the lower portions 90 of these relatively flat sides further materially strengthens the flange and the lugs while the flat sides also materially strengthen and reinforce the locking projections to 95 prevent their distortion or displacement, and it will be noted that each of the locking projections is preferably located adjacent to the apex of a pair of flat sides, (see 100 Fig. 3). That is to say, the corner formed by a pair of sides crosses substantially midway a line drawn through a locking projection, thus materially assisting in strengthening the projection, since the angle formed by a pair of relatively flat sides will be extended somewhat over a locking projection, 105 so as to bring the same substantially thereunder, and as this angle is somewhat stronger than the intermediate portions of the flat sides, it follows that the flexing of the locking projections due to the application 110 of the cap to the container is materially prevented, while at the same time this location

gives a somewhat wider locking face to the projection or lug at the center thereof.

Furthermore, by forming the skirt of a series of angularly connected friction surfaces so proportioned as to frictionally engage the outer faces of container projections, this will materially assist in preventing the lugs of the cap from rotating backward on the container and the consequent 10 premature separation of the cap from the container during the shipment or handling of the cap. Thus the cap will be maintained on the container both by these friction surfaces of large extent and by the lugs, which 15 is of considerable importance in the shipping and packing of containers or in the ordinary handling thereof on the shelves or stores or in the house.

In practice the cap will be provided with 20 an annular groove 7 to contact with a suitable liner not shown, thereby to effect the efficient sealing of the cap on the container.

I believe I am the first to provide a metal cap having a skirt or flange in which practically all of the skirt is of polygonal form, so proportioned as to frictionally engage the outer faces of container projections or which extend from substantially the top to substantially its lower edge of the skirt, and 30 therefore the first to provide a shallow flanged cap of such construction having locking projections at its lower edge, and also such a cap having a strengthened lower edge provided with locking lugs formed 35 therefrom.

It is to be understood that by describing in detail herein any particular form, structure, or arrangement, it is not intended to limit the invention beyond the terms of the 40 several claims or the requirements of the prior art.

Having thus explained the nature of my said invention and described a way of constructing and using the same, although without attempting to set forth all of the forms in which it may be made, or all of the modes 45 of its use, I claim:

1. A combined lug and friction holding container cap of metal comprising a top and 50 a shallow depending polygonally formed flange or skirt having a rolled, curled or beaded lower edge provided with inwardly extending locking lugs formed therefrom adapted to engage under inclined container 55 projections, such polygonal formation being so proportioned as to frictionally engage the outer faces of said inclined container projections and prevent the premature backward rotation of the cap.

2. A container cap comprising a top and 60 a depending polygonally formed flange or skirt of metal, such polygonal formation extending from substantially the top of the cap to its lower edge on the inside of said skirt and so proportioned as to frictionally

engage the outer faces of container projections.

3. A container cap comprising a top and a depending polygonally formed shallow flange or skirt of metal having a strengthened lower edge, such polygonal formation extending from substantially the top of the cap to its strengthened lower edge on the inside of said skirt and so proportioned as to frictionally engage the outer faces of container projections. 70

4. A container cap comprising a top and a depending polygonally formed shallow flange or skirt of metal, such polygonal formation extending from substantially the top of the cap to its lower edge on the inside of the skirt and so proportioned as to frictionally engage the outer faces of container projections, and locking projections below said polygonal surfaces. 80

5. A container cap comprising a top and a depending polygonally formed shallow flange or skirt of metal having a rolled, curled or beaded lower edge having inwardly extending locking projections formed therefrom, such polygonal formation extending from substantially the top of the cap to the rolled edge of the skirt on the inside and so proportioned as to frictionally engage the outer faces of container projections. 90

6. A metal cap comprising a top and a depending polygonally formed skirt or flange provided with inwardly extending projections therebelow, the angle formed by 100 a pair of said polygonally formed portions intersecting one of said projections.

7. A metal cap comprising a top having a depending polygonally formed flange or skirt provided at its lower edge with a strengthened portion having inwardly extending projections, the angle formed by a pair of said polygonally formed portions intersecting one of the locking projections. 105

8. A metal cap comprising a top having a depending shallow polygonally formed flange or skirt having its lower edge curled, rolled or beaded to reinforce the same and having formed therefrom inwardly extending locking projections, the angle of a pair of said polygonally formed portions intersecting said locking projections. 110

9. A metal cap comprising a top having a shallow decagonally formed flange or skirt terminating in a rolled, curled or beaded lower edge provided with a pair of diametrically opposed locking projections, the angle formed by a pair of said decagonally formed portions intersecting one of said projections. 115

10. A container cap comprising a top and a depending shallow flange or skirt of metal having a curled, rolled or beaded lower edge, and a pair of diametrically opposed inwardly extending locking lugs formed from such 120

rolled edge, the entire skirt from substantially the top of the cap to the rolled lower edge having on both the inside and the outside thereof a continuous series of wide angularly connected surfaces forming substantially a polygon so proportioned as to frictionally engage the outer faces of container projections.

11. A metal cap comprising a top having
10 a shallow depending flange or skirt provided with a curled, rolled or strengthened lower edge having a pair of diametrically opposed inwardly extending projections formed from such rolled edge, said skirt
15 having a polygonal formation from substantially the top to substantially the strengthened lower edge of the skirt, the angle of a pair of said polygonally formed portions intersecting a projection.

20 12. A metal cap comprising a top and a

depending shallow flange or skirt provided with a strengthened lower edge and inwardly extending locking projections, said skirt having a polygonal formation from substantially the top to substantially the lower 25 strengthened edge of the skirt, the angle formed by a pair of said polygonally formed portions intersecting a projection.

13. A container cap comprising a top and a depending polygonally formed flange or skirt of metal provided with a rolled, curled or beaded lower edge and inwardly extending locking lugs, such polygonal formation being so proportioned as to frictionally engage the outer faces of inclined container 35 projections.

Signed at Brooklyn, New York, this 5th day of July, 1923.

CHARLES HAMMER.
